(57) CLAIM

The ornamental design for a snow clearing apparatus, as shown and described.

DESCRIPTION

FIG. 1 is an isometric view of a snow clearing apparatus showing my new design;

FIG. 2 is a front elevational view thereof;

FIG. 3 is a rear elevational view thereof;

FIG. 4 is a right elevational view thereof;

FIG. 5 is a left side elevational view thereof;

FIG. 6 is a top planar view thereof;

FIG. 7 is a bottom planar view thereof; and,

FIG. 8 is an operational view thereof showing my design. The dashed broken lines represent environment and form no part of the claimed design.
